METHOD OF INTRODUCING AIR TO BURNERS OF REVERSING TYPE FURNACES

James L. Hartney, Chicago, Ill., assignor to United States Steel Corporation, a corporation of New Jersey

Original application March 9, 1950, Serial No. 148,619, now Patent No. 2,660,419, dated November 24, 1953. 10 Divided and this application May 27, 1953, Serial No. 357,739

6 Claims. (Cl. 263—52)

This invention relates to improved methods of introducing air to the burners of reversing type furnaces, for example for atomizing liquid fuel.

An object of the invention is to provide improved methods of preheating compressed air, selectively directing such air to either burner or set of burners in a reversing type furnace, and avoiding overheating of the equipment during changeovers.

A further object is to provide a method of directing flow of compressed air from a heating device to either burner or set of burners in a reversing type furnace and automatically maintaining continuous flow of such fluid through the heating device during changeovers and thereby preventing overheating of the heating device.

A further object is to provide improved methods of atomizing liquid fuel in open hearth furnace burners in which preheated compressed air is used as the atomizing fluid, thereby enhancing furnace efficiency over that obtained with steam as atomizing fluid.

In accomplishing these and other objects of the invention, I have provided improved details of structure, a preferred form of which is shown in the accompanying drawings, in which:

Figure 1 is a schematic view of a reversing type furnace equipped for introducing preheated air to the burners in accordance with the method of the present invention;

Figure 2 is a top plan view with parts broken away of a preferred construction of heat exchanger used in the apparatus shown in Figure 1;

Figures 3 and 4 are vertical sectional views of the heat exchanger taken respectively on lines III—III and IV—IV of Figure 2;

Figure 5 is an enlarged vertical sectional view of the heat exchanger showing the wall construction;

Figure 6 is a side elevational view with parts broken away of a preferred construction of a multiple diaphragm by-pass valve used in the apparatus shown in Figure 1; and

Figure 7 is an exploded sectional view of the operating mechanism of the valve shown in Figure 6.

Referring more in detail to the drawings:

In Figure 1, there is shown schematically a reversing type furnace 10, which can be for example an open hearth for manufacturing steel and which has two selectively operable burners 12 and 13 at opposite ends. The furnace is reversed periodically and thus is fired alternately from these two burners, as known in the art. There is shown at 14 an air compressor which directs compressed air through a line 15 to a receiving tank 16. From the tank the air passes via a line 17 into a heat exchanger 18, where the air is heated to a fairly high temperature which is maintained constant or nearly so. Line 17 preferably has a pressure regulator 19 and

2

a by-pass valve 20 for said regulator. The furnace, burners, air compressor, receiving tank, and pressure regulator may be of any standard construction; hence no more detailed description is deemed necessary. The preferred construction of heat exchanger is described more fully hereinafter.

One purpose for which air can be introduced to the burners in accordance with my method is for atomizing the fuel. In this instance the air is heated to a temperature preferably between 600° and 800° F., commonly being maintained at 700° F. The pressure commonly is maintained between 75 and 125 pounds per square inch, although none of these values are necessarily critical, as long as they are maintained constant or nearly so.

A line 21 extends from the heat exchanger and branches into lines 22 and 23 which extend respectively to burners 12 and 13. These lines contain normally closed, pneumatically operated diaphragm type valves 24 and 25 respectively for controlling flow of air to the burners. Inasmuch as these valves may be of any standard construction and per se are not part of the present invention, no more detailed description is deemed necessary. When the furnace is fired from either burner, the appropriate valve is opened and directs air to that burner.

The apparatus comprises a by-pass line 26 which discharges from pipe 21 into the atmosphere and which contains a valve 27. This valve is of the normally open, pneumatically operated double diaphragm type and is more fully described hereinafter. The apparatus comprises valve operating mechanism which automatically opens valve 27 unless either valve 24 or 25 is open, in which case it automatically closes valve 27. Thus the air continues to circulate through the heat exchanger when valves 24 and 25 are both closed as during changeovers in firing the furnace from one set of burners to the other, as is done periodically in operation of the furnace. Such circulation is needed to prevent overheating of the heat exchanger, since the temperature of air emerging from the heat exchanger can be fairly close to the maximum temperature which the heat exchanger can withstand. Also if the heat exchanger is overheated, there is subsequent difficulty in adjusting the air temperature to the desired constant.

The valve operating mechanism includes a control air line 28 which is connected with line 17 and thus receives compressed air from tank 16. Line 28 preferably contains a filter 29 and a pressure reducing valve 30, which both may be of any standard construction. Line 28 extends to a four-way control valve 31, to which are also connected to an exhaust line 32 and two lines 33 and 34 that extend to valves 24 and 25 respectively for operating these valves. Valve 31 has setting to connect line 28 with either line 33 or 34 and at the same time connect the other of these lines with exhaust line 32. Inasmuch as valves having such setting are known and per se are not part of the present invention, nor more detailed description is deemed necessary. Whenever the control valve admits air to line 33 or 34, valve 24 or 25 opens and air flows through that valve from the heat exchanger to one of the burners.

Air lines 35 and 36 extend from air lines 33 and 34 respectively to the by-pass valve 27. Whenever control valve 31 is actuated to relieve the pressure on the diaphragm of either of the normally closed valves 24 or 25 and thus close this valve, it also relieves the pressure that maintains the normally open by-pass valve closed. The by-pass valve thereupon opens and maintains air circula-

tion through the heat exchanger via by-pass line 26 and thus prevents overheating of the heat exchanger. The by-pass valve remains open until pressure is applied to the diaphragm of the other valve 24 or 25 to open this valve. At the same time pressure is applied automatically to the by-pass valve via line 35 or 36 and thus this valve closes, and circulation is resumed to one of the burners.

A preferred construction of heat exchanger 18 is shown in detail in Figures 2 to 5. The heat exchanger comprises an enclosure whose walls are formed of a heat insulation lining 37 supported by longitudinally extending channel-shaped casing members 38. Pairs of end plates 39 are interposed between successive tiers of insulating material and casings (Figure 5). A spacer 40 and a horizontal baffle 41 are interposed between each pair of end plates 39. The baffles are supported cantilever fashion from the end plates and thus are free to expand and contract. The baffles extend alternately from opposite sides into the interior of the heat exchanger as best shown in Figure 3 and define a sinuous course for circulating waste products of combustion from the furnace from which the heat is derived.

A fan 42 draws a portion of the products of combustion from furnace 10 into the lower portion of heat exchanger 18 through an inlet 43. These products of combustion pass through the heat exchanger in the course defined by baffles 41 and are expelled at the top through an outlet 44 into a stack 45 (Figure 1). The portion of such products which pass through the heat exchanger is governed by a damper 46 preferably located in outlet 44.

The compressed air is maintained at a substantially constant temperature, which may be controlled by regulating damper 46. Line 21 contains a temperature indicating device 47 and line 17 contains a flow indicating devices 48. Damper 46 is regulated in accordance with readings on these indicating devices to maintain a flow of products of combustion through the heat exchanger sufficient to heat the air to just the desired temperature. Although the damper may be regulated manually, the apparatus preferably includes metering controls, connected to the temperature and flow indicating devices 47 and 48 but not shown, for regulating the damper automatically. Inasmuch as such controls are known and do not per se form a part of the present invention, no more detailed description is deemed necessary.

The heat exchanger has a pair of manifolds 49 and 50, each of which is divided by partitions 51 and into a plurality of superposed compartments (Figure 4). The compartments on opposite manifolds are connected by U-shaped tubes 52, which extend between baffles 41 into the path of circulation of the products of combustion. Unheated compressed air is introduced from line 17 to the top chamber of manifold 49, whence it passes through tubes 52 to the top chamber of manifold 50. Such air then returns to the second chamber of manifold 49 via the next set of tubes 52. Air circulation between the manifolds continues through the entire height of the manifolds and the heated air finally discharges from the bottom chamber of manifold 49 into line 21, from which it may be directed to either set of burners as already explained.

Figures 6 and 7 show a preferred construction of by-pass valve 27. Said valve includes the usual body, stem and closures, which are not shown in detail, since they may be of any standard construction. The operating mechanism for this valve includes a pair of superposed flexible diaphragms 53 and 54 housed within the usual pressure chamber 55. A spring 56 normally urges the diaphragms to a retracted position against the back wall of the chamber and normally maintains the valve open. Air may be admitted to the space behind diaphragm 53 to close the valve, or air may be admitted to the space between the two diaphragms also to close the valve. The first of these spaces is connected to line 36 by a connection

57 in the back wall of the chamber. The second of these spaces is connected to line 35 by a connection 58 situated in a spacer ring 59 between the two diaphragms. The first space preferably has fillers 60 and the second fillers 61 to separate the diaphragms slightly from the end wall and from each other when either is retracted. Thus it is seen that the by-pass valve is closed whenever air is admitted behind either diaphragm on closing of either valve 24 or 25.

10 From the foregoing description, it is seen that I have provided an efficient method for introducing preheated compressed air to either burner or set of burners in a reversing type furnace. The air is continuously heated by heat derived from waste products of combustion and circulation of air is automatically maintained at all times including during changeover periods. Thus I have provided a method in which there is no likelihood of parts being overheated by failure to maintain air circulation.

The present application is a division of my copending application Serial No. 148,619, filed March 9, 1950, (now Patent No. 2,660,419 issued November 24, 1953) which in turn was a continuation-in-part of my application Serial No. 47,034, filed August 31, 1948 (now Patent No. 2,587,153 issued February 26, 1952).

25 While I have shown and described only a single embodiment of the invention, it is apparent that modifications may arise. Therefore, I do not wish to be limited to the disclosure set forth but only by the scope of the appended claims.

30 I claim:

1. A method of introducing air alternately to an opposed pair of burners in a reversing type furnace comprising preheating compressed air, directing such air to the burner through which the furnace is being fired while stopping flow of air to the other burner, and maintaining air flow through the preheating equipment during changeovers to the other burner while flow of air to both burners is stopped.

40 2. A method of introducing air alternately to an opposed pair of burners in a reversing type furnace comprising preheating compressed air with heat derived from waste products of combustion, directing such air to the burner through which the furnace is being fired while stopping flow of air to the other burner, periodically reversing the firing from one burner to the other, and maintaining flow of air through the preheating equipment during these changeovers while flow of air to both burners is stopped.

50 3. A method of introducing air alternately to an opposed pair of burners in a reversing type furnace comprising preheating compressed air with heat derived from waste products of combustion from the furnace, the air temperature being near the maximum the preheating equipment is capable of withstanding, directing such air to the burner through which the furnace is being fired, while stopping flow of air to the other burner, periodically reversing the firing from one burner to the other, and maintaining flow of air through the preheating equipment during changeovers to avoid overheating of this equipment while flow of air to both burners is stopped.

55 4. A method of atomizing liquid fuel in reversible open hearth furnaces comprising preheating compressed air, applying such air as atomizing fluid to a burner through which the furnace is being fired while stopping flow of air to the other burner, and maintaining flow of air through the preheating means during changeovers in firing from one burner to another while flow of air to both burners is stopped.

60 5. A method of atomizing liquid fuel in reversible open hearth furnaces comprising preheating compressed air with heat derived from waste products of combustion, applying such air as atomizing fluid to a burner through which the furnace is being fired while stopping flow of air to the other burner, periodically reversing the firing from one burner to another, and maintaining flow of air through

the preheating means during these changeovers while flow of air to both burners is stopped.

6. A method of atomizing liquid fuel in reversible open hearth furnaces comprising preheating compressed air with heat derived from waste products of combustion of the furnace, the air temperature being near the maximum the heating device is capable of withstanding, applying such air as the atomizing fluid to a burner through which the furnace is being fired while stopping flow of air to the other burner, periodically reversing the firing from one 10 burner to another, and maintaining flow of air through the heating device during these changeovers to avoid over-

heating the heating device while flow of air to both burners is stopped.
